[57] CLAIM

The ornamental design of saw guide, as shown and described.

DESCRIPTION

FIG. 1 is a generally top and right side perspective view of saw guide embodying the design of the present invention, and showing in broken lines exemplary illustration of the environment within which such design is intended to be used, by representing and exemplary object to be cut;

FIG. 2 is a generally top elevational view of the design of FIG. 1;

FIG. 3 is a generally front elevational view of the design of FIG. 1;

FIG. 4 is a generally back elevational view of the design of FIG. 1;

FIG. 5 is a generally bottom elevational view of the design of FIG. 1;

FIG. 6 is a generally right side elevational view of the design of FIG. 1; and,

FIG. 7 is a generally left side elevational view of the design of FIG. 1.

FIGS. 2 and 7 also represent an exemplary position of a movable plug usable with the design as part thereof, for placement in a selected one of the openings defined through the top of the design, as shown.
